A. H. BALLARD

OIL BURNING APPARATUS

Filed Feb. 1, 1923

Inventor:
Arthur H. Ballard,
by Emery Barth Jameson, Harvey
Atlys.

UNITED STATES PATENT OFFICE.

ARTHUR H. BALLARD, OF BOSTON, MASSACHUSETTS, ASSIGNOR TO BALLARD OIL BURNING EQUIPMENT COMPANY, OF BOSTON, MASSACHUSETTS, A CORPORATION OF MASSACHUSETTS.

OIL-BURNING APPARATUS.

Application filed February 1, 1923. Serial No. 616,401.

To all whom it may concern:

Be it known that I, ARTHUR H. BALLARD, a citizen of the United States, and a resident of Boston, in the county of Suffolk and State of Massachusetts, have invented an Improvement in Oil-Burning Apparatus, of which the following description, in connection with the accompanying drawings, is a specification, like characters on the drawings representing like parts.

This invention relates to oil burning apparatus and more particularly to controlling devices for automatically regulating the fuel supply.

The invention will be best understood by reference to the following description when taken in connection with the accompanying illustration of one specific embodiment thereof, while its scope will be more particularly pointed out in the appended claims.

In the drawings,—

Fig. 1 is a front elevation of an apparatus embodying one form of the invention, the electrical devices and connections, for sake of simplicity, being shown more or less diagrammatically;

Fig. 2 is a sectional detail in elevation on the line 2—2 in Fig. 1 showing the air pressure control for the oil supply valve; and

Fig. 3 is a sectional plan view on the line 3—3 in Fig. 1 of the burner and pilot light.

Referring to the drawings and to the embodiment of the invention there illustrated, I have shown the same applied to a steam boiler 5 adapted for steam heating purposes, but the invention as to many of its features is applicable to other uses. Herein the burner 7 is located just outside of the combustion chamber of the boiler 5, the casing of the latter having an opening 9 through which the burner is adapted to project its fuel, the latter consisting of an atomized mixture of air and liquid hydrocarbon.

The burner may be of any suitable type, but herein for illustrative purposes it is shown as provided with a fuel nozzle 11 (see Fig. 3) connected to the oil supply pipe 13, the nozzle being surrounded by an annular chamber 15 which communicates with an air supply pipe 17. The air and oil, both under pressure, are delivered to a mixing chamber 19 whence they pass through the perforated head 21 to a second

mixing chamber 23 and thence through the 55 orifice 25 into the fire or combustion chamber of the boiler through the opening 9 where they are burned. A constantly burning pilot light 27 fed by the gas supply pipe 29 is located just in front of the burner 7 so as 60 to ignite the fuel as soon as the supply of the latter is turned on.

Oil is supplied to the pipe 13 from the oil tank 31 from which it is drawn through the pipe 33 by means of the gear pump 35 65 or other pumping device. The oil may be supplied directly to the pipe 13 and burner 7 under the pressure of the gear pump 35, but in order to best cooperate with the control devices herein provided and to afford 70 an oil supply under a constant head or pressure, it is first conveyed through the pipe 36 to the supply tank 37 and thence to the pipe 13, the tank 37 being sufficiently elevated to provide the desired head. An over- 75 flow pipe 38 carries any surplus of oil back to the oil tank 31.

An electric motor 39 is herein provided which is connected through suitable gearing 41 to drive not only the oil pump 35, but also an air pressure device such as the blower 43 to feed air under pressure to the air supply pipe 17. The motor 39 is automatically started and stopped by regulating devices, hereinafter described, to feed or 80 supply air and oil under pressure as required through the respective supply pipes 13 and 17. A pressure gauge 47 is provided in the air supply pipe, and in the oil pipe 13 also a needle valve 49 to regulate the 85 rate of oil flow. In the air pipe 17 near the burner there may be provided a check valve 51 so arranged as to permit the free passage of air to the burner but preventing oil from backing up into the air pipe, should 90 the burner become clogged.

In order to prevent the supply of oil to the burner, except when air under an adequate pressure is being supplied through the air supply pipe 17, there is also provided in the oil supply pipe 13 an oil cut-off valve adapted to be operated when the lever 55 is lowered to cut off the supply of oil. This valve is so arranged that it closes whenever the pressure in the air 100 supply pipe drops below a predetermined amount, and it also provides for adequate air supply under pressure at the burner noz- 105

zle before oil can be supplied thereto. For this purpose the lever 55 is connected by the link 57 to the end of an arm 59 (see Fig. 2), the latter pivoted at 61. The arm 59 5 rests through a knife-edged connection 63 on the upper end of a vertically movable rod 65. The lower end of the latter is connected to a plate 67, the underside of which is exposed to air pressure from the 10 pipe 17 through the connection 69, but is normally depressed by the corrugated or bellows-like metallic connection 71. Weights 73 and 75 are provided to make the device 15 delicately responsive to the required pressure, the two weights being adjusted so that when the rod 65 moves down the lever arm swings to drop the link 57 and close the oil valve. When the requisite air pressure is 20 present in the pipe 17, the plate 67 lifts 25 against the resiliency of the corrugated connection 71, swinging the lever arm 59 about its pivot 61 to the dotted line position shown, raising the link 57 and valve arm 55, thereby opening the oil supply valve. This oil 30 valve remains open so long as the necessary air pressure is maintained, but as soon as it ceases or drops below the required amount the compressed and elastic connection 71 forces the plate 67 down, allowing the 35 weight 73 to drop the link 57 and close the oil valve. The oil supply is therefore promptly shut off as soon as the air supply fails from any cause, and any tendency of the oil flow to persist after the stoppage of 40 the motor, due to a siphoning action or other cause, is stopped. Another advantage is secured through the use of this valve and particularly in connection with the automatically controlled motive devices, herein 45 after described, for feeding oil and air. In the absence of such a valve or its equivalent, the oil tends to reach the burner when the motive devices are started up before sufficient air pressure has been built up to properly atomize the oil. This excess of oil pressure would not only result in leakage of the burner, but would tend also to back the oil up through the air supply pipe and thereby further to interfere with the function 50 of the burner, particularly where the direct pressure of the gear pump is relied upon to supply the oil to the pipe 13 without the interposition of the gravity feed tank 37. Through the provision of the oil 55 cut-off valve and its air pressure control, however, the oil is prevented from reaching the burner not only until air has been supplied thereto, but until the air supply has built up sufficient back pressure to lift the lever arm 59 and open the oil valve. This 60 insures an air pressure at the burner in advance of the oil and the proper functioning of the burner under all conditions of usage.

To further regulate the fuel supply as required, the motor 39 is so connected that it

is automatically stopped if the pilot light becomes accidentally extinguished or if the temperature in the space to be heated rises above a predetermined limit, or in the further event that steam pressure in the boiler 70 becomes excessive. Such regulation may be effected in various ways, but herein the motor supply circuit 77 passes through a switch 79, the latter being drawn toward an open position by means of a spring 81 and held 75 in its closed position by electro-magnetic means, such as the solenoid magnet 83. One terminal of the magnet is connected to a source of current supply, such as the storage battery 85, and the latter to the movable 80 member of a thermostat 87 which is located in the space to be heated.

When the temperature falls below the required amount the movable member of the thermostat engages the contact 89 and closes 85 the circuit thereat. When the temperature rises above the required limit the movable member of the thermostat moves to the blind contact 91 and breaks the circuit, thereby deenergizing the solenoid, opening the motor circuit and stopping the motor and the fuel supply. As soon as the temperature drops below the required amount movement 90 of the thermostat in the opposite direction to the contact 89 takes place, the solenoid 95 is again energized and the burner again started up.

The contact 89 is connected through the conductor 93 with a bi-metallic thermostat member 95 which is positioned immediately 100 over the flame from the pilot light 27, although, for clearness, it is shown at one side thereof in Fig. 1. While the pilot light is burning such thermostat member is positioned to engage with the contact 97 and 105 maintain the magnet circuit closed through the conductor 99. As soon as the pilot light becomes extinguished the cooling of the bi-metallic thermostat 95 causes the latter to swing down and away from the contact 97, 110 breaking the circuit and deenergizing the magnet irrespective of the position of the thermostat 87. The motor is thereupon stopped and the fuel supply cut off until the pilot light is again lighted. 115

Preferably the motor 39 is also subject to the control of a pressure responsive device, and for this purpose the supply circuit 77 passes through the switch 101, the latter being normally drawn to a closed position by 120 the spring 103 but having a connection 105 to the lever arm 106 and pressure responsive device 107, the latter being such that on a rise in boiler pressure beyond a predetermined amount the lever arm swings so as to 125 pull the connection and open the switch 101, thereby stopping the motor and the fuel supply.

While I have herein shown for the purposes of illustration one specific embodiment

ment of the invention, it is to be understood that the same is herein shown for the purpose of illustration and that the details of construction and relative arrangement of parts as well as the application of the invention may be varied within wide limits without departing from the spirit thereof.

Claims:

1. A fluid fuel burner having a mixing chamber therein presenting an orificed nozzle, air and oil conduits communicating with the mixing chamber, means for supplying air under pressure to the air conduit, a gravity feed device for supplying oil under substantially constant pressure to the oil conduit, a pressure responsive device in the air conduit arranged to be actuated by the air pressure and means operatively connected to be controlled by said pressure responsive device for permitting a supply of oil to the mixing chamber from said gravity feed device only when a predetermined air pressure has been obtained whereby there is insured a substantially constant pressure relation between the air and the oil at their respective points of discharge to the mixing chamber.
2. A fluid fuel burner having a mixing chamber therein presenting an orificed nozzle, air and oil conduits communicating with the mixing chamber, means for supplying air to the air conduit, a gravity feed device for supplying oil under substantially unvarying pressure to the oil conduit, pressure responsive means associated with the air conduit and means in the oil conduit operatively connected to be actuated by the air pressure therein, valve means in the oil conduit operatively connected to the pressure responsive means arranged to permit a supply of oil at the mixing chamber from said gravity feed device only when a predetermined air pressure has been obtained to insure a substantially constant pressure relation between the air and the oil and their respective points of discharge to the mixing chamber during and after initial combustion at the burner.
3. A fluid fuel burner having a mixing chamber therein presenting an orificed nozzle, air and oil conduits communicating with the mixing chamber means for supplying air under pressure to the air conduit, a gravity feed device for supplying oil under substantially constant pressure to the oil conduit, pressure responsive means associated with the air conduit and means in the oil conduit operatively connected to said pressure responsive means for permitting a supply of oil at the mixing nozzle from the gravity feed device only when a predetermined air pressure has been obtained, and a check valve in the air conduit to prevent oil from backing up therein.

In testimony whereof, I have signed my name to this specification.

ARTHUR H. BALLARD.
